US00D365988S

United States Patent [19]
Clarke, III

[11] **Patent Number:** **Des. 365,988**
[45] **Date of Patent:** ****Jan. 9, 1996**

[54] **CAN END WITH OVAL TEAR PANEL**

[75] Inventor: **Milton W. Clarke, III**, Chesterfield County, Va.

[73] Assignee: **Reynolds Metals Company**, Richmond, Va.

[**] Term: **14 Years**

[21] Appl. No.: **24,577**

[22] Filed: **Jun. 15, 1994**

[52] **U.S. Cl.** **D9/438**

[58] **Field of Search** D7/328; D9/370, D9/434-438, 441, 446-447, 449, 451, 502, 518, 520; 215/255; 220/253, 266, 269, 271, 273, 306; 222/541

[57] **CLAIM**

The ornamental design for a can end with oval tear panel, as shown and described.

DESCRIPTION

FIG. 1 is a top plan view of a first embodiment of a can end with oval tear panel, showing my new design;

FIG. 2 is a top plan view of a second embodiment thereof; and,

FIG. 3 is a side elevational view thereof, all other side elevational views being identical thereto.

The underside of the can end with oval tear panel is plain and unornamented.

The broken lines shown in the above drawing figures are for illustrative purposes only and form no part of the claimed design.

UNITED STATES PATENT AND TRADEMARK OFFICE
CERTIFICATE OF CORRECTION

PATENT NO. : Des. 365,988

Page 1 of 3

DATED : Jan. 9, 1996

INVENTOR(S) : Milton W. Clarke, III

It is certified that error appears in the above-identified patent and that said Letters Patent is hereby corrected as shown below:

The Title page, should be deleted to be replaced with the attached title page.

The drawing sheet, consisting of Figs. 1 and 2, should be deleted to be replaced with the drawing sheet, consisting of Figs. 1 and 2, as shown on the attached page.

Signed and Sealed this
Third Day of December, 1996

Attest:

Attesting Officer

BRUCE LEHMAN

Commissioner of Patents and Trademarks
